UNITED STATES PATENT OFFICE

SIGWART RUPPEL, OF FRANKFORT-ON-THE-MAIN, GERMANY

HIGH TENSION CIRCUIT INTERRUPTER

Application filed August 27, 1928, Serial No. 302,368, and in Germany August 30, 1927.

My invention relates to high tension circuit interrupters of the gas-blast type and has for its principal object the provision of an improved circuit breaker of the aforesaid 5 type capable of quickly extinguishing high tension power arcs.

In my copending application Serial No. 217,438, filed September 3, 1927, there is disclosed and claimed a method of and apparatus for interrupting high tension arcs by means of a gas blast directed between the electrodes. The present invention is an improvement thereover and is directed to auxiliary arcing means for aiding interruption 15 of arcing by the gas blast.

In accordance with my invention one contact or electrode is provided with a channel, as a diverging gas passage, and the other electrode is arranged to contact with the first-named electrode at the restricted portion of said passage, said point of contact forming the main current carrying area. Auxiliary arcing means coacting with the aforesaid electrodes are disposed within the diverging 25 passage beyond the main contact surfaces so that upon separation of the electrodes the gas blast directed between the same is effective to transfer arcing to the auxiliary arcing means within the diverging passage 30 where it is extinguished.

My invention will be more fully set forth in the following description referring to the accompanying drawings, and the features of novelty which characterize my invention will 35 be pointed out with particularity in the claims annexed to and forming a part of this specification.

Referring to the drawings, Fig. 1 is a fragmentary view, partly in section, of a circuit 40 interrupter of the gas-blast type embodying my invention; Figs. 2, 3, 4, 5 and 6 are detailed views, partly in section, of different forms of electrodes and arcing means; Figs. 7 and 9 are fragmentary views, partly in section, of other forms of electrode structures 45 wherein the main contacts are separately controlled; Fig. 8 is a view, partly in section, illustrating electrode structure and operating means therefor; Fig. 10 is a fragmentary view, partly in section, of another

form of circuit interrupter having main and auxiliary contacts arranged to coact in accordance with my invention, and Fig. 11 is a sectional view showing another form my invention may take. 55

There is illustrated in Fig. 1 the electrode structure of a gas-blast circuit breaker comprising movable contact structure 1 and a stationary contact or electrode 2 forming a diverging exhaust passage, at the restricted portion of which the movable contact or electrode structure 1 is normally disposed. In accordance with my invention as set forth in my aforesaid copending application, separation of the contact surfaces is accompanied 60 by a blast of gas through the diverging passage to extinguish arcing between the electrodes. 65

I have found that under certain conditions the arc produces a counter-pressure to the gas blast directed between the electrodes, thereby reducing the velocity and extinguishing action of the gas blast. Under certain conditions upon opening movement of the electrode, wherein the inner or rod-like contact 70 is moved in opposite direction to the gas blast, the arc travels in a direction opposite to that of the gas blast so that the arc persists and is not extinguished. This disadvantage is avoided, in accordance with my 75 invention, by transferring the arc from the restricted portion of the passage to the diverging portion which is provided with auxiliary arcing means so that the arc is finally 80 extinguished in the diverging portion. In this arrangement the pressure waves produced by the arc extend in the direction of the increasing cross section of the diverging passage, that is, in the direction of the gas blast 85 itself, so that a serious counter-pressure is not exerted by the arc. The counter-pressure of the arc is further minimized by the use of auxiliary arcing portions composed of a metal resistant to vaporization, as tungsten 90 or the like. Where the mass of the arc stream and its conducting constituents are reduced to a minimum, interruption of arcing by the gas blast is greatly facilitated even though 95 the amperage and current density are high. 100

To this end the rod portion 3 of the mov-

able electrode is provided at its upper end with an auxiliary contact portion 4 arranged to engage in the closed circuit position the coacting auxiliary contact portions 6 forming part of the electrode 2. The arrangement is such that upon opening or downward movement of the rod 3 the main contact surfaces at 1 separate prior to separation of the auxiliary arcing contacts 4 and 6. It shall be understood that this may be accomplished in a number of different ways, the construction shown being merely an illustration of the principle involved. The rod 3 is provided with a lost-motion connection with the auxiliary arcing contact 4 comprising resilient means as a spring 7 arranged to bias upwardly the stem 8, which is in guided and sliding relation to the rod 3, so that the contact 4 is normally biased into engagement with the coacting arcing portions.

The main contact portions 1 are resiliently secured to the contact rod 3, as by laminated springs 9. The springs serve normally to bias the contact portion 1 into engagement with the inner wall of the nozzle-like electrode 2 at the restricted portion thereof.

The operation of the device is as follows: When the rod contact 3 is lowered to open the circuit interrupter the contacts 1 will be drawn away from the stationary electrode by the springs 9 which normally exert a radial force on the contacts 1. Separation of the contact surfaces at 1 therefore effects transfer of the circuit through the arcing means within the diverging exhaust portion. During the initial opening movement of rod 3 the spring 7 maintains the auxiliary contacts in engagement until the stop member 8' is engaged by the rod 3. Separation of the auxiliary arcing contacts occurs coincident with or subsequent to a blast of gas which is directed into the casing 16 and through the nozzle-like electrode 2. The auxiliary arcing contacts are preferably composed of a material, as tungsten or the like, which is resistant to vaporization and produces a minimum amount of metallic vapor in the arc stream.

When the gas blast is directed between the electrodes, the gas flows at high velocity past the open contact surfaces at 1 into the diverging portion of the exhaust passage to interrupt the arc at the auxiliary arcing means 4 and 6. By arranging the main contact surfaces at the restricted portion of the passage, flashover or shifting of the arc from the auxiliary back to the main contact is substantially precluded, the arc instead being blown further into the diverging portion of the passage.

In order to produce at the initial opening of the switch a strong gas blast, the main contacts in their closed position may wholly or partly close the restricted portion of the passage, the passage being opened upon open-

ing of the main contacts. During the switching operation the passage at the main contacts will be traversed by gas with high velocity and force. Separation of the electrodes may be effected in any suitable manner, as by well known mechanical operating mechanisms or by pneumatic means generally shown in Fig. 11.

The relation between the arc gap and the source of gas pressure or gas reservoir is preferably such that the gas blast is directed across the arc with minimum loss of pressure. In other words, it is desirable that the gas reservoir be closely positioned with respect to or form a part of the switch chamber itself.

In Fig. 2 there is illustrated movable electrode structure arranged to close the restricted portion of the passage in the closed circuit position. In this case flexible bands 10 are disposed between the contact portions 1 and the auxiliary arcing contact 4 and rod 3, respectively. The control of the contacts 1 by the rod 3 is as previously described.

In Fig. 3 a generally similar structure is shown wherein the springs 9 are combined with the flexible bands 10, the upper ends being free and only their lower ends being secured to the rod 3.

In similar structure shown by Fig. 4 the laminated springs are replaced by a helical spring 9a which is inserted between the auxiliary contact 4 and the rod 3, the operation being generally as above described.

In place of separate auxiliary contacts, the auxiliary arcing means may comprise an annular member 12 as illustrated in Figs. 5 and 6. As shown, the annular member 12 is mounted within the diverging part of the exhaust passage and is flared in conformity with the nozzle exhaust. The arcing portion 4 engages one end of the member 12 in the manner of a valve engaging its seat. As in the previous instance, the gas blast is directed through the restricted portion of the passage between the electrodes and extinguishes the arc within the diverging portion at the annular member 12. Fig. 6 shows a similar arrangement wherein the contact 4 is provided with an extension 13. In this case the annular member 12 and the extension 13 may be wholly or partly composed of special materials as graphite and the like.

Fig. 7 discloses another form of electrode structure wherein the main contacts 1 are supported by a pair of levers 14 pivotally mounted as at 14a on the rod 3. The lower ends of the lever are provided with cam faces arranged to engage cam blocks 15 disposed within the casing 16. Resilient means, as an elliptical spring 17, tends to bias the levers 14 apart and into engagement with the blocks 15. Upon opening of the switch the levers 14 are moved away from the blocks 15 by the downward movement of the central rod 3 so

that the spring 17 is effective to force the lower ends of the levers apart and separate the main contacts at 1. The levers 14 may, of course, be arranged so that the desired degree of movement of the contacts 1 may be obtained. The contacts 1 may wholly or in part consist of a metal which is resistant to vaporization for reasons previously set forth. If desired, the nozzle-like electrode 2 may be 10 of the resilient segmental type. In this case the nozzle is split into segments as at 2a and surrounded by an annular compression spring 2b or the like.

Upon opening of the switch an arc is first 15 produced between the contacts 1 and the electrode 2 coincident with the gas blast through the exhaust passage. Under the influence of the gas blast the arc is transferred from the contacts 1 to the auxiliary contact 4 and particularly to the arcing tip 13 of the auxiliary contact. In consequence thereof the arc travels into the widened portion of the exhaust passage and is here extinguished by the blast. The gas flows at high velocity 25 past the contacts 1 thereby preventing re-striking or flashover of the arc to the main contacts.

Fig. 8 illustrates another form of electrode structure and operating means therefor comprising a movable rod contact 4 and a stationary nozzle-like contact 2. Mounted within the nozzle portion 2 are contacts 33 biased as by springs 34 into engagement with rod contact 4. Suitable means 35 are provided for adjusting the tension of the spring 34. The contacts 33 are disposed at the restricted portion of the diverging passage where the gas velocity is high and are provided at their contact surfaces, or entirely, 40 with a special metal which is resistant to vaporization or chemically inert, as rustless steel, tungsten, nickel, black lead, and the like. In order to minimize breaking up of the gas flow by the contacts they may be 45 stream lined. If desired, strips or ribs 32 may be provided on the contact or arcing surface of the rod 4 to coact with the contacts 33. The strips 32 may be composed of a metal resistant to vaporization, as above 50 described, and may be stream lined and in connection with the extension 13.

If it is desired to introduce an extinguishing agent, as carbon tetrachloride or the like, a nozzle 36 may be provided below the contact 33. Such an agent, which may be in the form of a liquid, gas or powder may be admitted to separately controlled passages, as by an ejector or the like (not shown), or entrained by the gas flowing through the nozzle.

The pneumatic operating means shown by way of example comprises a piston 4' suitably arranged to cause reciprocatory movement of the rod 4. The piston is mounted 65 within a cylinder 4" which is connected at

one end to a source of pressure generally indicated at P. Admission of gas to the cylinder causes opening of the switch. The switch casing 16 is likewise connected as by a pipe 16' to the source of pressure so that the gas blast may be concurrent with opening movement of the rod contact 4.

Fig. 9 shows a switch generally similar to that shown in Fig. 7. The levers 14 to which the main contacts 1 are connected are pivoted on the central rod 3 at 14b, the inner ends of the levers being connected to a rod 18. A spring 17b connected at one end to the arcing portion 4 and at its other end to the inner ends of the levers 14 tends to bias the main contacts into normal engagement. Upon opening of the switch the rod 18 is first moved downwardly, the rod 3 remaining in position. Accordingly, the contacts 1 are rotated out of engagement with the stationary electrode 2 producing an arc between portions 1 and 2. Under the influence of the gas blast the arc at once is transferred to the arcing portion 4 and to the diverging wall of the electrode 2. The arc is therefore extinguished within the diverging exhaust. Since the spring 17b is placed under tension by the initial movement of the rod 18 the arcing portion 4 is shortly thereafter moved downwardly also and withdrawn from the exhaust passage. The arc, however, is extinguished by the blast before the portion 4 reaches the restricted part of the passage.

Fig. 10 illustrates another form of auxiliary arcing means. The nozzle electrode 2 is mounted within a casing 16a which is secured to the top of the insulating switch casing 16. The nozzle 2 is provided with spring buffers 19 and adjusting means 20 therefor arranged so that limited axial movement of the nozzle 2 within the casing 16a is permitted. In the present case when the pressure of the gas within the casing 16 overcomes the pressure of springs 19 the nozzle 2 is moved upwardly and lifted away from the stationary central rod 3 including the arcing portion 4 and the tip extension 13. The auxiliary arcing means 6 forming part of the nozzle 2 are arranged beyond the restricted portion of the passage so as to be within the diverging gas flow. Accordingly, the arc is transferred, upon separation of the electrodes at the restricted portion, to the auxiliary arcing means 6—13 within the diverging passage and is there extinguished.

It will be understood, of course, that the resilient contact structure illustrated in Fig. 1 may be used in the above arrangement if desired.

There is likewise shown in Fig. 11 electrode structure of the character above described arranged for relative movement. A stationary central rod 3 formed as a tubular member open at its upper end and a mov-

able nozzle electrode 2 are arranged to make contact at I, this point being substantially at the restricted portion of the diverging exhaust passage and at the base of the arcing pin or portion 4. Any suitable means may be provided for reciprocating the nozzle 2. The nozzle 2 may be in sliding conducting engagement with the conducting terminal structure II. The gas under pressure will be supplied by way of the tubular member to the outlets or passages 3a in the central rod 3. In this case the diverging part of the nozzle, with the arc, moves downwardly and the gas blast from the passages 3a is directed on the arc so as to transfer the same from the engaging surface at the restricted portion of the exhaust passage to the tip of the arcing pin or portion 4 which is carried at the end of rod 3 in fixed proximity to the gas exhaust passages 3a. It will, therefore, be apparent that the gas exhaust from the outlets 3a bears a fixed space relation to the arcing pin so that a gas stream of substantially uniform velocity on the engaging surface of the arcing pin is maintained during the switch opening operation. Accordingly, in this operation the arc is extinguished within the diverging part of the passage. A particular advantage of the modification described lies in its simplicity of design. It will be apparent, of course, that relative movement may be obtained as by having the central rod movable upwardly or by movement of both electrodes.

It should be understood that my invention is not limited to specific details of construction and arrangement thereof herein illustrated, and that changes and modifications may occur to one skilled in the art without departing from the spirit of my invention.

I claim:

1. A high tension circuit interrupter comprising a pair of electrodes, one of said electrodes having a nozzle-like expanding passage within which the other electrode is disposed in the closed circuit position of the interrupter, the main contact surfaces of said electrodes coacting adjacent the throat of said passage, arcing means extending within the exhaust expanding portion of said passage, and means for directing gas at high velocity between said electrodes and through said nozzle-like passage so that the arc formed upon separation of said main contact surfaces is extinguished at said arcing means within said exhaust portion.
2. A high tension circuit interrupter comprising relatively movable electrodes, one of said electrodes surrounding the other in the closed circuit position and provided with a diverging exhaust passage, auxiliary arcing means extending within said passage, said electrodes engaging in the closed circuit position adjacent the entrance of said exhaust passage, and means for directing a gas at

high velocity between said electrodes upon separation thereof through said diverging passage for transferring the arc formed upon separation of said electrodes to said auxiliary arcing means within said diverging exhaust passage.

3. A circuit breaker for interrupting high tension power arcs comprising a fluid chamber, an electrode having a nozzle-like passage mounted at one end of said chamber, said passage communicating at one end with said chamber and exhausting into a region of low pressure, a coacting rod electrode mounted within said chamber and engaging said first-named electrode within said passage, the main contact surfaces of said electrodes being disposed adjacent the entrance of said passage, auxiliary arcing means comprising part of said rod electrode disposed in the exhaust portion of said passage, and means for directing a gas at high velocity from said chamber through said passage and between said electrodes upon opening movement thereof so that the arc formed upon separation of said electrodes is transferred to said auxiliary means and extinguished by an expanding jet of high-velocity gas within said exhaust portion.

4. A high tension circuit interrupter comprising an electrode provided with a passage defined by a constricted and a diverging exhaust portion, a coacting electrode disposed within said passage in the closed circuit position of said interrupter, the main contact surfaces of said electrodes engaging adjacent said constricted portion, auxiliary arcing contacts associated with said electrodes disposed in said diverging exhaust portion, means for effecting separation of said main contact surfaces prior to separation of said auxiliary contacts, and means for directing a gas at high velocity through said constricted portion between said main contact surfaces and through said exhaust portion whereby the arc formed between said auxiliary contacts is interrupted in said exhaust portion beyond the main contact surfaces.

5. A high tension circuit interrupter comprising a pair of electrodes, one of said electrodes having a nozzle-like passage within which the other electrode is disposed in the closed circuit position of the interrupter, main current-carrying contacts disposed at the constricted portion of said passage, auxiliary arcing contacts associated with said electrodes disposed within the exhaust portion of said passage, means including a lost-motion connection for effecting opening movement of the main contacts prior to separation of the auxiliary contacts, and means for directing a gas at high velocity upon separation of said electrodes past said main contacts and through said exhaust portion for interrupting therein the arc formed at said auxiliary contacts.

6. A high tension circuit interrupter comprising a fluid chamber, an electrode having a nozzle-like passage mounted at one end of said chamber, said passage being in communication with said chamber and with a region of low pressure at its exhaust portion, a coacting electrode mounted within said chamber contacting with said first-named electrode at the entrance of and within said passage, auxiliary contacts carried by each of said electrodes extending into said exhaust portion, means for effecting electrode opening movement prior to separation of the auxiliary contacts, and means for directing gas from said chamber at high velocity between said electrodes and through said exhaust portion to interrupt the arc at said auxiliary contacts.

7. A circuit breaker for interrupting high tension power arcs comprising a fluid chamber, an electrode having a passage including a constricted and a diverging exhaust portion mounted at one end of said chamber, said passage communicating at one end with said chamber and exhausting into a region of low pressure, a coacting rod electrode mounted within said chamber and engaging said first-named electrode adjacent the constricted portion of said passage, said rod electrode provided with an arcing portion extending within the exhaust portion of said passage, coacting arcing portions mounted within the exhaust passage in the other electrode, the main contact surfaces of said electrodes being disposed adjacent said constricted portion, and means for directing a gas at high velocity from said chamber between said electrodes upon opening movement thereof and through said passage whereby the arc formed adjacent said constricted portion is transferred to said arcing portions and interrupted within said exhaust portion.

8. A circuit breaker for interrupting high tension power arcs comprising a sleeve-like electrode having a passage defined by constricted and diverging exhaust portions, a fluid chamber in communication with said passage at one end thereof, said passage exhausting into a region of low pressure, a coacting rod electrode mounted for reciprocal movement within said chamber for engaging said sleeve electrode within said passage and adjacent the constricted portion thereof, said rod electrode provided with an arcing tip of material resistant to vaporization at high temperatures extending within the exhaust portion of said passage, the main contact surfaces of said electrodes being disposed adjacent the constricted portion of said passage, and means for directing a gas from said chamber between said electrodes at a velocity sufficient to overcome the pressure of the arc formed between said electrodes whereby said arc is interrupted at said arc-

ing tip within said exhaust portion in an expanding jet of high velocity gas.

9. A circuit interrupter of the gas-blast type comprising relatively movable electrodes, one of said electrodes having a diverging exhaust passage and the other of said electrodes comprising a rod member normally engaging said first-named electrode adjacent the restricted portion of said passage, and means directing gas at high velocity between said electrodes upon separation thereof and through said passage, said rod member including an arcing tip arranged to extend appreciably within said diverging passage in the direction of gas flow after separation of said electrodes.

10. In a gas blast circuit breaker including a pair of relatively movable contacts between which a gas blast is directed for extinguishing arcing, one of said contacts comprising a nozzle-like structure forming the exhaust passage of the gas blast, the other coacting contact comprising a pin engaging and surrounded by said nozzle contact in the closed circuit position, and means forming a gas passage from a source of pressure to an outlet in fixed proximity to the engaging surface of said coacting contact, so that the exhaust from said outlet impinges directly upon said engaging surface during the opening of the circuit breaker.

11. A gas blast circuit breaker comprising a nozzle contact and a coacting contact comprising a pin engaging and surrounded by said nozzle contact in the closed circuit position, a tubular member communicating with a source of gas pressure and forming a passage for directing gas to the point of separation of said contacts and through said nozzle contact, said contact pin carried by and positioned a fixed distance beyond the open end of said tubular member.

In testimony whereof I affix my signature.
SIGWART RUPPEL.
